Image of Home brand ceramic plate.

Primary Examiner—Philip S Hyder
Assistant Examiner—Cynthia Underwood(57) **CLAIM**

We claim the ornamental design for a sidewall region of a disposable plate, as shown and described.

DESCRIPTION

FIG. 1 is a perspective view of a sidewall region of a disposable plate;

FIG. 2 is a side view of FIG. 1, all other side views being identical thereto;

FIG. 3 is a top plan view of FIG. 1;

FIG. 4 is a bottom plan view of FIG. 1; and,

FIG. 5 is a cross section view of FIG. 1 along lines 5—5 of FIG. 1.

Broken lines in the drawings form no part of the present design.
